Thomas Howe.

UNITED STATES PATENT OFFICE

EARL C. MAXWELL, OF BROOKLYN, NEW YORK.

TANK FOR SPRINKLER SYSTEMS.

1,315,522.

Specification of Letters Patent.

Patented Sept. 9, 1919.

Application filed July 12, 1916. Serial No. 108,950.

To all whom it may concern:

Be it known that I, EARL C. MAXWELL, a citizen of United States, residing at Brooklyn, New York, have invented certain new and useful Improvements in Tanks for Sprinkler Systems, of which the following is a specification.

This invention relates to the structure and arrangement of tanks, etc., usually on the roof of the building, from which a fire protective sprinkler system within the building is supplied.

In many locations the fire underwriters require two independent sources of supply and for this and other reasons it is now customary in systems of this character to employ two tanks on the roof. One of these tanks, known as the "gravity tank", supplies water under pressure of gravity. The other tank, known as the "pressure tank", has a liquid with air confined above it. This air is compressed and exerts a corresponding pressure upon the liquid tending to expel it.

It has been customary to mount the gravity tank ten or fifteen feet above the roof upon a structural steel frame-work, while the pressure tank has been ordinarily mounted close to the roof in a housing or bulk-head.

The pipes leading from the gravity tank have been protected from freezing by means of suitable insulation such as is provided by boxing them in. The housing or bulk-head inclosing the pressure tank, piping, valves, etc., has been suitably heated to prevent freezing.

An object of the present invention is to provide a structure by which the supporting frame work for the gravity tank may be dispensed with and a simpler, stronger and more shapely appearing structure provided.

A further object of the invention is to provide a structure whereby the housing of the pressure tank may be dispensed with.

Other and ancillary objects of the invention will appear hereinafter.

In the accompanying drawings which illustrate the invention,

Figure 1 is a vertical axial section of a structure, arrangement of tanks, etc., embodying the invention.

Fig. 2 is a similar view of a modified construction the upper portion being shown in elevation, and

Fig. 3 is a similar view of a further modi-

fication, the upper portion here also being shown in elevation.

Referring to the drawings, and first to Fig. 1, the pressure tank has its axis vertical with the side walls formed by the cylinder 1 and the convex end heads 2 and 3. The gravity tank has the side walls 4 and cover 5 and is supported by the pressure tank, the upper end 2 of the pressure tank being exposed to the liquid of the gravity tank and forming a closure for that tank at its bottom. In this case, however, the end of the pressure tank does not form the entire bottom of the gravity tank, this bottom having the overhanging portion 6 outside the pressure tank and secured thereto. It will of course be understood that suitable vents will be made in the roof 5 or otherwise, so that air may have access to permit the fluid in the gravity tank to be discharged under the pressure of gravity.

The tanks may be made of various materials but preferably the pressure tank is constructed of boiler steel riveted together as shown and the gravity tank of wood. The lower end of the pressure tank rests on brackets 7 which are supported on I beams 8 resting upon the building frame or walls. The housing 9 is placed about the pressure tank, the overhanging bottom 6 of the gravity tank forming the roof of the space inclosed by the housing. A suitable heater such as a coiled steam pipe may be arranged in the housing to prevent the temperature about the pressure tank from becoming too low. This steam coil may be connected with the steam heating plant of the building so that the heating in the tank housing is necessarily of the proper temperature when the building is suitably heated for occupancy by the tenants. The gravity tank may also contain a steam heating coil. Within the housing of the pressure tank a pipe 10 leads from the gravity tank to a pipe union 11 from which connection is made through the valve 12 and a check valve 12' with the pipe 13 leading to the sprinkler system inside the building. The check prevents backward flow into the gravity tank. A pipe 14 having a valve 15, connects with the union 11 and provides a drain for the gravity tank. Upon opening the valve 15, water may be drained from the gravity tank. When the valve 12 is opened the gravity tank is placed in communication with the pipe 13 leading to the sprinkler system.

The valve 17 controls connection of

the pressure tank with pipe 13 and the valve 18 controls connection with the drain pipe 16. The tanks may be supplied with suitable water gages, ladders and trap doors for gaining access, and other appurtenances well known in this art without requiring further explanation, including any well known or suitable means for pumping or otherwise supplying the tanks with water.

10 It will be observed that all the connections from the tanks to the supply pipe leading to the sprinkler system are within the heated inclosure so as to be protected from injury or stoppage by freezing.

15 Referring now to Fig. 2, the gravity tank 20 and pressure tank 21 are of the same diameter, the upper end 22 of the pressure tank forming the entire bottom of the gravity tank. In this case of course there is no overhanging of the bottom of the gravity tank so that the roof 23 of the inclosing housing for the pressure tank is structurally separate from the tanks. In this structure the pipe 10' leading to the gravity tank 20, communicates with the drain pipe 14' and also with the pipe 13' leading to the sprinklers, the arrangement of the pipes and valves being similar to that shown in Fig. 1. Also the pipe 19' leading to the pressure tank 21 may, 20 by means of an arrangement of valves similar to that described in connection with the pipes of Fig. 1, be connected with the drain pipe 16' or the sprinkler feed pipe 13'.

25 The arrangement of apparatus in Fig. 2 is similar to that in Fig. 1 except that the gravity and pressure tanks are of substantially the same diameter, the gravity tank having no overhanging in the case of Fig. 2.

30 Referring now to Fig. 3, the gravity tank 24 is of the same diameter as the pressure tank 25. The pressure tank, however, is of a different structure. It is mounted with its major axis vertical and has convex heads 26 and 27 and a cylindrical body 28 similar to the pressure tanks of the preceding figures. It differs, however, in that it has a central axial passage or chamber inclosed by the tube 29. This tube is preferably circular and flanged at one end where it is riveted to the end head 27. The other end of the tube extends to the roof making a chamber closed from the weather within the pressure tank and at the center thereof. This leaves the space for the fluid within the pressure tank annular, surrounding the tube 29. The central tube 29 forms a fluid tight joint with the end heads 26 and 27 of the pressure tank. Extending laterally from the tube 29 is a tube 30 making fluid tight joints with the tube 29, and wall 28. The end of the tube 30 is closed by a heat insulating door or cover 31. Upon the removal of this door access may be had to the various valves, gages, etc., with which it is desirable to equip tanks and 35 which must be protected from freezing. It

will be observed that the tubes 29 and 30 inclose a space which is cut off from the atmosphere when the door 31 is in place, and this inclosed chamber may contain a heater such as a steam coil 32 which may be connected with the heating system of the building. Within this chamber are all the connections which it is necessary to keep from freezing thus there is running through the tube 29 a pipe 33 communicating with the 70 gravity tank and with the sprinkler supply pipe 34. Communication through the pipe 33 is controlled by the valve 35, the operating stem 36 of which is accessible through the tube 30, and a check valve 30' preventing 75 back flow into the gravity tank. The pipe 37 communicates with the pressure tank and also with the pipe 34 through the valve 38. The stem 39 of the valve 38 is controlled by means of a hand wheel 40 accessible through the tube 30 and rotating the stem 39 by means of beveled gears 41; also the gage glass 42 for the pressure tank may be spaced within the range of vision through the tube 30. The drain pipe 43 connects through a 80 valve 44 with the pipe 33. This may be cut off when desired and the tanks placed in connection with the sprinkler supply pipe; also the heated chamber within the pressure tank 85 serves to prevent it from freezing. The necessity for a housing is therefore done away with.

85 Also, if desired, the gravity tank may be provided with a central tube 45 which may receive heated air as by being placed in communication with the heated tube 29 of the pressure tank, the tube 45 being riveted at one end to the bottom of the gravity tank and having its other end 46 closed.

90 While the invention has been illustrated 105 in what are considered its best applications it may have other embodiments without departing from its spirit and is not therefore limited to the structures shown in the drawings.

95 What I claim is:

1. The combination with a pressure tank of a gravity tank supported by said pressure tank and having its bottom closed by a wall of said pressure tank, and a fire extinguisher 110 system connected with said tanks.

2. The combination with a pressure tank of a gravity tank having one of its walls closed by a wall of said pressure tank, and a fire extinguisher system connected with 115 said tanks.

120 3. The combination with a cylindrical pressure tank having convex ends and with its axis vertical, of a gravity tank supported by said pressure tank, the upper end of said pressure tank forming a closure for the bottom of said gravity tank, and a fire extinguisher system connected with said tanks.

125 4. The combination with a pressure tank having a chamber therein extending from 130

one wall to another and surrounded by the liquid chamber, of heating means located in the first mentioned chamber, a fire extinguisher system and means connecting said system with said liquid chamber.

5. The combination with a pressure tank having a cylindrical body with its axis vertical and convex end heads, and a central vertical passage extending from one end 10 head to the other of a fire extinguisher system connected with said tank.

6. A pressure tank having a heating chamber, and a liquid chamber, said chambers being closed against each other and said 15 heating chamber being closed at its upper end, and a fire extinguisher system connected with said liquid chamber.

7. The combination with a pressure tank of a gravity tank supported by said pressure 20 tank and having its bottom closed by a wall of said pressure tank; a fire extinguisher system; a pipe leading from said gravity tank to said system; a pipe leading from said pressure tank to said system;

valves in said pipes controlling the communication from said tanks to said fire extinguisher system respectively, and of the tanks with each other, whereby either of said tanks may be singly connected with said system.

8. The combination with a cylindrical 30 pressure tank having convex ends and with its axis vertical, of a gravity tank supported by said pressure tank, the upper end of said pressure tank forming a closure for the bottom of said gravity tank; a fire extinguisher 35 system; a pipe leading from said gravity tank to said system; a pipe leading from said pressure tank to said system; valves in said pipes controlling the communication from said tanks to said fire extinguisher 40 system respectively, and of the tanks with each other, whereby either of said tanks may be singly connected with said system.

In testimony whereof, I have signed my name to this specification, this 6th day of 45 July, 1916.

EARL C. MAXWELL.
